UNITED STATES PATENT OFFICE.

ALLISON J. THOMPSON, OF CLEVELAND, OHIO.

LAMP HANGER.

Application filed December 22, 1922. Serial No. 608,446.

This invention relates to improvements in lamp hanger structures and application of the same.

The object of this invention is to provide a lamp hanger structure which is entirely and effectively closed against the elements more particularly to so house the latch mechanism, contacts and electric wiring as well as the sheave wheel, and cable or chain for lowering the lamp, so as to protect such parts from dirt, moisture or corrosive gases.

More especially, it is an object of this invention to provide removable closure means for the lower part of the lamp hanger to protect the inner mechanism and also to render the body of the lamp hanger more rigid.

Another object of this invention is to improve the appearance of the installation.

Other objects of the invention will appear from the following description and claims when considered in connection with the accompanying drawings.

Figure 1 is a vertical section of my improved device; Fig. 2 is a cross sectional view taken on the line 2-2 of Fig. 1; Fig. 3 is a side elevation of a modified form of sheave housing structure.

The canopy member 1 of the upper hanger member has fixed therewithin the contacts 2 which are adapted to be engaged by the floating contacts 3 carried by the lower hanger member, which member includes the post 4. This post 4 carries a pivoted dog or latch member adapted for locking engagement with a notch provided in the slotted tubular member 5 which depends from the top wall of the canopy member 1. The structure thus far referred to is substantially the same as that shown in my copending application, Serial No. 394,341 to which reference may be had for a fuller understanding of the same. In the present form, however, the depending flange 7 is shorter than that in the copending application, as other means are here provided for protecting the spring member 8 against the elements. This spring 8 serves the same purpose as in the companion application, namely, to provide tension between the two hanger members so as to press the lower contacts into engagement with the upper contacts and also to maintain the latch or dog member 5 in locked engagement with the tubular member. The rope or cable 9 is adapted to support the lower hanger mem-

ber in the same manner as in the companion case and extends upwardly through the hollow post 4 and tubular member 5 and out through the housing around the sheave to which reference will be made later. Fig. 1 shows the parts in latched position and, just as in my prior application referred to, by pulling on the rope 9 the lower hanger member is raised slightly, thereby compressing spring 8, until the latch parts release, whereupon the lower hanger member and the parts carried thereby can be lowered to the ground.

The outlet member 10 for the electric wires has screw threaded engagement at 11 with the lower end of the stem member 4 and is provided with diametrically opposed openings 12 for the wires 13. The closure member 14 which is adapted to engage and close the bottom of the canopy member 1 is provided with an opening 15 surrounding the outlet member 10 with sufficient clearance, as indicated in the drawings, and is provided about its upper marginal edge portion with the seat or shoulder 16 and the upwardly extending rib or flange 17, sufficient clearance being provided at this point also to allow for any irregularities in the surfaces of the parts, without a frictional binding effect.

The spring 18 engages the flange 19 of the closure member 14 and is maintained under sufficient tension to hold the closure 14 in place by means of the nut 20 on the lower part of the outlet member 10. This spring functions in the same way as the spring 8 in that, when the parts are closed and latched as in Fig. 1, the lower canopy is yieldingly held to its seat and the lower hanger member may be elevated to release the latching parts and permit the lamp to be lowered. Also, the two springs 8 and 18 obviously permit both the contacts and the lower canopy to yieldingly reach their respective seats upon closing and latching of the hanger. The extreme lower portion of the outlet member 10 is threaded as indicated at 21 for attachment of the lamp. A flange 22 is provided on the outlet member 10 for cooperation with the flange 19 in the closure member so as to maintain the closure member 14 upon the outlet member 10 until the closure member is assembled so as to engage the lower edge of the canopy member. The particular engagement between the closure member 14 and the lower edge of the canopy member 1 in combination with the

enclosed sheave housing constitutes a means of sealing the lamp hanger against entrance of dirt, moisture or corrosive gases, without a frictional binding between members 1 and 14.

The sheave housing structure contains a chamber in which is mounted the sheave 23 for the cable 9. As shown in Fig. 1, the sheave housing structure is formed also with a duct 24 for leading the electric wires from the conduit into the top of the canopy member. Suitable openings are provided in the top of the canopy member for the passage of the cable and the electric wires 25, the rib or boss 26 being provided entirely about the openings 27 and 27' and projecting up into the corresponding opening in the sheave housing so as to exclude the elements. Sufficient clearance is allowed between the rib or boss 26 and the depending portion 28 of the sheave housing structure so as to take care of minor irregularities in the surface of these parts. In this manner, a substantially sealed connection is provided so as to protect the inside structure against the elements. The sheave housing structure is secured to the top of the canopy member by means of the ear portions 30, through which extend the same bolts as are employed in securing the tubular member 5 to the top of the canopy member in the same manner as disclosed in the former application above referred to. In the form shown in Fig. 1, the duct 24 for the wires is provided with a screw-threaded portion 31 for attachment to a pipe conduit 32, the end portion of the duct as shown in this form of device extending in the opposite direction from the screw-threaded portion 33 provided for attachment to a threaded pipe or conduit 34 for the cable 9. Suitable ears 40, 41 are provided for suspension of the lamp hanger.

One side wall of the sheave housing is provided with an opening to receive a circular disc cover 43 which is provided with a correspondingly formed flange for engagement in the opening. This cover need not necessarily be circular but may be of other forms. This cover is provided with a central opening in registry with an opening provided in the opposite wall of the sheave housing for the bolt 45 which secures the closure 43 in position, and upon which is mounted the sheave 23. The sheave housing structure, when the closure 43 is in position, is entirely and effectively closed, that is, when it is attached to the top of the canopy member and when the conduits 32 and 34 are assembled therewith. The curved tapering surfaces of the closure 43 at the seat 42 provide means of centering the closure 43 upon assembly of the parts and provides also means of insuring true running of the sheave.

In the modified form shown in Fig. 3 the duct 46 for the electric wires extends in the same direction as the duct for the cable, but

is otherwise of the same construction as the first form of device.

In my improved lamp hanger structure, I have provided means for effectively sealing the parts against attack by the elements such as natural precipitation and other moisture, as well as corrosive gases and dirt; and the closure member 14 serves also as a means of providing a more rigid arrangement whereby swaying movement of the lamp is reduced to a minimum. The conduits which are attached to the sheave housing structure, for enclosing the electric wires and cable, provide also a means of not only protecting these parts against the elements but also afford a means of bracing the entire lamp hanger structure. In my present arrangement, I have eliminated also the use of openings in the side walls of the canopy member for passage of the electric wires, as commonly found in the older forms of such devices. With all, my improved device proves not only efficient in service, but also presents a very neat and attractive appearance.

What I claim is:

1. A lamp hanger structure, comprising a main hanger member, a lamp hanger member, means for securing said members together, said main hanger member having a canopy member enclosing said securing means, an inverted canopy for closing said first named canopy against the entrance of foreign elements, said inverted canopy having a central aperture for the lamp hanger member, and a spring surrounding said lamp hanger member and engaging said inverted canopy so as to provide a yielding engagement therebetween.

2. A lamp hanger structure, comprising upper and lower hanger members, releasable means actuated by relative vertical movement between said members for latching them together, two canopies, one carried by each of said members, and together adapted to completely enclose the hanger members, and yielding means between one of said canopies and the member on which it is mounted, thereby permitting yielding relative movement between said members for actuation of the latching parts when the canopies are engaged with each other.

3. A lamp hanger structure, comprising upper and lower hanger members, cooperating contact means on said members, the contact means on one member being yieldingly mounted, and uninterrupted closure canopies on said members, one of said canopies being yieldingly mounted, whereby the canopies and contacts both yieldingly reach seating engagement upon relative approach of said members, and when engaged, the contacts are completely enclosed by the canopies.

4. A lamp hanger structure, comprising upper and lower hanger members, releasable latching means between said members, co-

operating contact means on said members, the contact means on one member being yieldingly mounted, uninterrupted closure canopies on said members, one of said canopies being yieldingly mounted, whereby the canopies and contacts both yieldingly reach seating engagement upon relative approach of said

members, and when engaged the latching means and contacts are completely enclosed by the canopies.

In testimony whereof I hereby affix my signature.

ALLISON J. THOMPSON.
